(57) **CLAIM**

The ornamental design for a miter saw, as shown and described.

DESCRIPTION

FIG. 1 is front perspective view from the left side of an embodiment of a miter saw showing our new design.

FIG. 2 is a left side elevational view of the embodiment.

FIG. 3 is a right side elevational view of the embodiment.

FIG. 4 is a front elevational view of the embodiment.

FIG. 5 is a rear elevational view of the embodiment; and,

FIG. 6 is a top plan view of the embodiment.

In the above drawings, any views not shown thereof do not form a part of the invention.

1 Claim, 6 Drawing Sheets
